CENTRIFUGAL CASTING MOLDS

Johann Seeba, Peter Biefang, and Alfred Simonis, 5 Gelsenkirchen, Germany, assignors to Eisenwerke Gelsenkirchen, Aktiengesellschaft, Gelsenkirchen, Germany

Application August 12, 1952, Serial No. 303,882

Claims priority, application Germany August 13, 1951

11 Claims. (Cl. 22—113.5)

The present invention relates to centrifugal casting 15 molds.

More particularly, the present invention relates to elongated, tubular, centrifugal casting molds and the construction of the inner surface of the same.

It is old to form irregularities on the inner surface of 20 centrifugal casting molds. For example, such irregularities may be formed by blasting the inner surface of the mold with steel shot or by etching the same. Such irregularities are of a haphazard pattern. Also, it is known to form on the inner surface of centrifugal molds of 25 the above type grooves which extend parallel to the longitudinal axis of the mold and parallel to the transverse axis of the mold.

The purposes of the above mentioned irregularities or grooves are to improve the action of the mold, by better transferring to the material in the mold the centrifugal force of the rotating mold, and to better enable the mold to withstand the high temperatures of the molten metal placed therein by enabling the inner surface of the mold to expand more freely without producing great 35 stresses on the mold wall.

However, the above mentioned grooves have serious disadvantages. Thus, when the molded article is removed from such a mold, it very often has along its outer surface elongated grooves extending axially along the 40 mold article, and such grooves are very undesirable. Moreover, with molds having an inner surface provided with axially and circumferentially extending grooves, the axially extending grooves gradually become wider and the circumferentially extending grooves gradually close 45 up and disappear so that with this type of mold the grooves do not hold their shape for a long period of time. Also, with such grooves the distances between the centers of the squares or rectangles formed by the 50 grooves and the corners of these squares or rectangles are different from the distances between centers of these squares or rectangles and the centers of the sides of the same. As a result the inner surface of the mold is subjected to non-uniform tensions.

One of the objects of the present invention is to provide a centrifugal casting mold which will not cause the molded article to have longitudinal grooves on its outer surface when it is removed from the mold.

Another object of the present invention is to provide a mold with inner grooves which will hold their original shape for a long period of time and will not easily become closed up.

Yet another object of the present invention is to provide on the inner surface of a mold grooves which will produce uniform tensions on the inner mold surface.

A further object of the present invention is to provide a mold whose inner surface is capable of holding, in a uniformly distributed manner, a powder, such as ferro-silicon powder.

A still further object of the present invention is to provide on the inner surface of a centrifugal mold a pat-

2

tern of grooves which form between themselves areas capable of becoming automatically grouped in different ways to best suit the particular molding conditions.

An additional object of the present invention is to provide a process for easily and quickly forming grooves of the above type on the interior of the mold.

A still additional object of the present invention is to prevent the formation of cracks at those parts of a mold which are subjected to relatively high stresses.

With the above objects in view the present invention mainly consists of an elongated, tubular, centrifugal casting mold formed on its inner surface with a plurality of elongated grooves which intersect each other and which are all inclined to the longitudinal axis of the mold and to an axis normal to the longitudinal axis, these grooves preferably making an angle of between 40 and 50° with these axes. In a preferred form of the invention, the grooves are arranged in a honeycomb pattern.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a fragmentary, longitudinal section through a mold constructed in accordance with the present invention;

Fig. 2 is a fragmentary, sectional view of a part of the inner surface of the mold of Fig. 1, showing on an enlarged scale the grooves therein;

Fig. 3 is a fragmentary, developed view on an enlarged scale of the inner mold surface of a mold construction in accordance with the present invention;

Fig. 4 is a fragmentary, developed view on an enlarged scale of the inner mold surface of another mold constructed in accordance with the present invention;

Fig. 5 is a fragmentary, longitudinal sectional view through a mold of relatively small size constructed in accordance with the present invention; and

Fig. 6 is a fragmentary, longitudinal sectional view through a mold of relatively large size constructed in accordance with the present invention.

Referring now to the drawings, and more particularly to Fig. 1, there is shown in this figure a part of a mold having its inner surface formed with grooves 9 and 10 which may extend along the entire length of the inner mold surface. It will be seen that these grooves 9 and 10 do not extend circumferentially and longitudinally along the mold. They instead are inclined to the longitudinal mold axis and an axis normal thereto and preferably make an angle of between 40° and 50° with these axes, so as to form between themselves square or rhomboid areas. Fig. 2 shows the shape of the grooves on an enlarged scale, and it is seen that these grooves are substantially V-shaped in cross-section. The grooves 9 are parallel to each other, and the grooves 10 are parallel to each other. It has been found from experience that where the centrifugal mold is made of steel, these grooves have the longest life and produce the best results when they are located from each other by a distance of between 1

55 and 2 mm., preferably 1.5 mm.

In Fig. 3 there is shown on an enlarged scale a part of 65 a developed inner surface of a mold constructed in accordance with the present invention. In this form of the invention the grooves 3 are formed in a honeycomb pattern, and they are arranged so that no part of the grooves 3 extends parallel to the longitudinal axis 1 or the transverse axis 2 of the mold. The individual areas included 70 between the grooves 3 are further divided by grooves 4

finer than the grooves 3. Although in the particular example shown the grooves 4 divide the area between the grooves 3 into triangles, it is also possible to provide additional grooves, similar to grooves 4, dividing these areas into four cornered areas or into haphazard areas. Instead, of a six cornered honeycomb arrangement as shown in Fig. 3, it is possible to use patterns having areas formed with a different number of corners, such as five or eight cornered honeycomb patterns, and it is not essential that all the sides of the areas formed by the honeycomb pattern of grooves be straight. The grooves 4 cooperate with the grooves 3 to provide an inner mold surface capable of holding a powder in a uniformly distributed manner. The centers of the areas formed by grooves 3 are substantially equidistant from the corners and sides of these sub-areas so that a non-uniform stress in the inner mold surface is avoided to a great extent.

In Fig. 4 there is shown on an enlarged scale a developed view of the inner surface of a further embodiment of a mold constructed in accordance with the present invention. In this embodiment of the invention, three sets of parallel, equally spaced grooves intersect each other to form areas 5 in the shape of equilateral triangles, and, as is apparent from Fig. 4, none of the grooves are parallel to the longitudinal axis 1 of the mold. During operation of a mold constructed in accordance with Fig. 5, the high temperature acting on the inner mold surface will cause the latter to expand as a result of the stresses therein, and during such expansion, the triangular areas 5 will automatically group themselves to produce honeycombed six cornered patterns, such as 6, 7 and 8 of Fig. 4, depending upon the particular stresses produced in the mold during operation thereof. These various honeycomb patterns will be best suited for the particular conditions within the interior of the mold. It is also possible for the triangular areas 5 to group themselves together to form an irregular honeycomb pattern. This particular form of the invention is particularly advantageous because it is very simple to form the areas 5 on the inner mold surface.

With conventional centrifugal molds, the larger stresses take place in the cylindrical part of the mold. However, it has been found that the molds constructed in accordance with the present invention, where the grooves are inclined to the longitudinal axis of the mold and an axis normal thereto, the cylindrical part of the mold remains undamaged for a long period of time, and the first cracks start to appear in those parts of the mold which are located next to the ends of the uniform cylindrical part.

In order to avoid the formation of cracks in these parts of the mold which are subject to relatively high stresses, the constructions of Figs. 5 and 6 are provided. In these figures there are shown portions of two molds having formed therein grooves 9 and 10 of the same construction as was described above in connection with Fig. 1. It has been demonstrated by experience that the above-described centrifugal casting molds of relatively small size, i. e. below 200-250 mm. diameter, tend to form predominantly longitudinally extending cracks in the highly stressed regions thereof, and the above-described molds of relatively large size, i. e. over 250-300 mm. diameter, tend to produce predominantly circumferential cracks in their highly stressed regions. The mold of Fig. 5 represents a mold of a relatively small size and is formed in its region of extremely high stresses with the longitudinal grooves 11, while the mold of Fig. 6 represents a mold of relatively large size and is formed in its highly stressed region with the circumferential grooves 12.

Where the grooves on its inner surface of the mold, such as the grooves 9 and 10, have a depth of approximately 0.2 mm., experience has shown that it is best to make the grooves 11 or 12 with a depth of approximately 0.5 mm. Also, where these grooves, such as grooves 9 and 10, are located apart from each other by a distance

of 1-2 mm., as was described above, experience has shown that it is best to locate the grooves 11 or the grooves 12 apart from each other, by a distance of from 2 mm. to 10 mm. Thus, where the grooves 9 or the grooves 10 are located apart from each other by a distance of 1.5 mm., the grooves 11 or the grooves 12 would be located apart from each other by a distance of approximately 6 mm.

Centrifugal casting molds of the type described above may have their inner surfaces formed with the above-described grooves in a number of different ways. For example, it is possible to turn the grooves into the inner surface of the mold with a machine tool. One of the most preferred ways of forming the indentations on the inner surface of the mold is to use a knurled wheel having on its outer surface sets of ridges which intersect each other and are inclined to the longitudinal and transverse axes of the knurled wheel. This knurled wheel is pressed against the interior surface of the mold, and the mold and knurled wheel are moved with respect to each other so that the knurled wheel moves with respect to the mold circumferentially about the inner surface thereof and moves axially with respect to the same, at the proper rate, so that the desired indentations are in this way formed on the interior of the mold. The advantages resulting from this process of forming the grooves on the interior of the mold are not only in its simplicity but also in the fact that the material of the mold is compressed by the knurled wheel so as to greatly strengthen the mold.

It will be understood that each of the elements described above, or two or more together, may also find a useful application in other types of centrifugal molds differing from the types described above.

While the invention has been illustrated and described as embodied in centrifugal molds having on their inner surfaces grooves which are inclined to the longitudinal and transverse axes of the molds, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. An elongated, tubular, centrifugal casting mold having an inner surface formed with a plurality of elongated, intersecting grooves which are inclined to the longitudinal axis of the mold and an axis normal to the longitudinal axis and make an angle of between 40° and 50° with at least one of said axes.

2. An elongated, tubular, centrifugal casting mold having an inner surface formed with a plurality of elongated, intersecting grooves which are inclined to the longitudinal axis of the mold and an axis normal to the longitudinal axis and make an angle of between 40° and 50° with both of said axes.

3. An elongated, tubular, centrifugal casting mold having an inner surface formed with a plurality of grooves arranged in a honeycomb pattern and all being inclined to the longitudinal axis of the mold.

4. An elongated, tubular, centrifugal casting mold having an inner surface formed with a plurality of grooves arranged in a honeycomb pattern and all being inclined to the longitudinal axis of the mold, said inner surface having the portions thereof located between said grooves formed with additional grooves finer than said

first-mentioned grooves and dividing said portions into polygonal areas.

5. An elongated, tubular, centrifugal casting mold formed on its inner surface with three sets of parallel grooves, said sets intersecting each other and all pairs of adjacent grooves of said three sets of grooves being located apart from each other by equal distances, and said grooves forming between themselves areas on the inner surface of the mold having the shape of equilateral triangles, all of said grooves being inclined to the longitudinal axis of the mold and an axis normal to said longitudinal axis.

6. A centrifugal casting mold as defined in claim 5 and wherein all of said grooves are of the same depth.

7. A centrifugal casting mold as defined in claim 5 and wherein each pair of adjacent grooves of said three sets of grooves are located apart from each other by a distance of approximately 1.5 mm.

8. An elongated, tubular, centrifugal casting mold having a diameter of less than 250 mm., being formed 20 on its inner surface with intersecting sets of grooves all of which are inclined to the longitudinal and axis of said mold and an axis normal to said longitudinal axis, and being formed at parts thereof which are subjected to relatively great stresses with an additional set of grooves 25 substantially parallel to the longitudinal axis of said mold.

9. An elongated, tubular, centrifugal casting mold having a diameter of more than 250 mm., being formed 30 on its inner surface with intersecting sets of grooves all 30 of which are inclined to the longitudinal axis of said

mold and an axis normal to said longitudinal axis, and being formed at parts thereof which are subjected to relatively great stresses with an additional set of circumferential grooves located about the longitudinal axis of said mold.

10. A centrifugal casting mold as defined in claim 8 and wherein said additional set of grooves are approximately 0.5 mm. deeper than said intersecting sets of grooves and located apart from each other by a distance of from 2 to 10 mm.

11. A centrifugal casting mold as defined in claim 9 and wherein said additional set of grooves are approximately 0.5 mm. deeper than said intersecting sets of grooves and located apart from each other by a distance of from 2 to 10 mm.
